FOLDING PANEL SYSTEM WITH MOVABLE VERTICAL LOUVERS

Charles D. Dushek, Lisle, Ill., assignor to Sears, Roebuck and Co., Chicago, Ill.

Filed May 12, 1971, Ser. No. 142,860

Term of patent 14 years

Int. Cl. D6—06

U.S. Cl. D6—139

FIG. 1

FIG. 2

FIG. 3

FIG. 4

FIG. 5

FIG. 6

FIG. 7

FIG. 8

FIG. 1 is a front perspective view of a folding panel system with movable louvers showing my new design, said louvers being in a closed position, with the side of said system not shown the same as the side shown in FIG. 1; and

FIG. 2 is a sectional view taken substantially along the line 2—2 of FIG. 1.

FIG. 3 is a fragmentary front perspective view on an enlarged scale of my design; and

FIG. 4 is a front perspective view showing the folding panel system with movable louvers when said louvers are in an open position.

FIGS. 6, 7 and 8, are respectively, sectional views taken substantially on lines 6—6, 7—7 and 8—8 of FIG. 1.

I claim:

The ornamental design for a folding panel system with movable vertical louvers, as shown and described.
